MULTIPLEX COMMUNICATION SYSTEM

François Charles Pierre Henroteau, Ottawa,
Ontario, CanadaApplication March 5, 1941, Serial No. 381,906
In Belgium March 6, 1940

3 Claims.

(Cl. 250—9)

This invention relates to multiplex communication systems and is a development from the apparatus described in my prior United States application Ser. No. 252,030 filed January 20, 1939.

The system of the present invention comprises a central station and a number of substations so arranged that wireless communication may be had simultaneously and on the same wave length between the central station and all or some of the substations, and it may be used for example in a naval or aerial squadron to permit communication between the squadron commander's unit and other units.

The underlying idea of the invention is that operations at the central station and substations may be synchronized and that the selection by a substation of the signals intended for it or the transmission from that station of a signal for the central station without overlapping with signals transmitted from other substations results from the different positions occupied in the receiving or transmitting devices at each different substation of certain operating parts of such devices.

According to the invention the system comprises a central station including an envelope containing a number of mosaics (the term "mosaic" meaning wherever used in this application an assembly of the type used in many television systems and consisting of a multiplicity of mutually insulated tiny conductive electron emissive elements and a uniformly conductive backing layer, the elements and this layer often being carried on a central dielectric plate), means for scanning said mosaics simultaneously by different slow moving electron releasing beams and means for scanning said mosaics successively by a single fast moving electron releasing beam in a time no greater than that elapsing during the scanning of one mosaic by one of the slow moving beams, and a number of substations no greater than the number of mosaics at the central station and each including an envelope, the envelope at each different substation containing only a single mosaic corresponding in position to a different mosaic at the central station, means for scanning each single mosaic by a slow moving electron beam synchronously with the scanning by the slow moving electron beams at the central station, and means for scanning each single mosaic by a fast moving electron beam synchronously with the scanning of the mosaic at the central station with which it corresponds in position by the first mentioned fast moving electron beam. The central station and each substation

preferably includes a transmitter and a receiver so that two way communication is possible. In such a case an envelope forms part of each transmitter and each receiver. In the transmitter 5 each slow moving electron beam is modulated by a message (i. e., any intelligence or portion of any intelligence, such as sound or pictures or writing, which may be represented by electrical vibrations) to be sent, thus recording this message on a mosaic area, and the fast moving beam converts the record so formed into signalling impulses, whereas at the receiver the fast moving beam is modulated by the signalling impulses received, thus recording these on a mosaic area 10 or in the case of the central station or a number of such areas and the slow moving beam or beams reconstitute the message or messages from the record or records so formed. In order to prevent beats due to phase displacement of the carrier wave coming in to the receiver at the central station simultaneously from the emitters at a number of central stations, means are preferably provided at each of the latter to prevent transmission of the carrier wave except while it is modulated by a message.

The invention will now be described in more detail by reference to the accompanying drawing of one suitable form. In the drawing—

Figure 1 is the transmission at the central station;

Figure 2 is the receiver at the central station; Figure 3 is the receiver at a substation, and Figure 4 is the transmitter at a substation.

The transmitter of Figure 1 is similar to the transmitter shown in Figure 1 of my prior application and comprises an envelope 1 containing three mosaics 4, 5 and 6 having a common central dielectric plate 3 and a common conductive backing connected through an appropriate amplifying and modulating device 14 to an emitting antenna 15. Associated with the mosaics is a conventional electron gun 7 housed in a pocket in the envelope. At the other end of the envelope and facing the mosaics is an electron emissive plate 8 which has three electron guns 94, 95 and 96 associated with it, each including a modulating electrode 10 connected to, for example, a microphone 11. Between the plates is an accelerating electrode 12 and inside the envelope an electronic lens in the form of a condensive coil 13.

The receiver of Figure 2 is similar to the transmitter of Figure 1 but with the electron guns reversed and the conductive backings of the mosaics separate. Thus, electron guns 14, 75 and 76 are associated with the mosaics 41, 51 and 61 re-

spectively and the conductive backing of each mosaic is connected through an appropriate amplifying device 18 with, for example, a pair of earphones 19. On the other hand one electron gun 9 is associated with the plate 81 and its modulating electrode 10 is connected through an appropriate demodulator and amplifier 16 with a receiving antenna 17.

At each substation the transmitter may be identical with the transmitter at the central station except that there is only one mosaic and only one electron gun associated with the electron emissive plate. Figure 4 shows the transmitter for one substation. Here there is a mosaic 4a corresponding in position to the mosaic 4 in Figure 1, and mounted conveniently on a plate 3a identical with the plate 3 in Figure 1 and there is one electron gun 94a, corresponding to the gun 94 of Figure 1, associated with the plate 8a identical with the plate 8 in Figure 1.

Similarly, the receiver at each substation may be identical with the receiver at the central station except that there is only one mosaic and associated electron gun. Thus in Figure 3, which shows the receiver for the substation of which the transmitter is shown in Figure 4, there is only a mosaic 41a corresponding in position to the mosaic 41 of Figure 2, and an associated electron gun 74a. As in Figure 4, the mosaic is conveniently on a plate 31a identical with the plate 31 of Figure 2.

Each of the two other substations, which a system having the central station transmitter and receiver of Figures 1 and 2 could include, would have the same receiver and transmitter as those shown in Figures 3 and 4 except that the mosaics would correspond in position with the mosaics 51 and 5 and 41 and 4 respectively.

The system described operates generally as described in my prior application in connection with the contemporaneous transmission of a number of messages over a single transmission channel. In Figure 1, the slow-moving electron beams from the guns 94, 95 and 96 are caused to scan simultaneously different areas of the plate 8 corresponding to the mosaics 4, 5 and 6 respectively, the intensity of these beams being modulated by the modulating electrodes 10 in accordance with messages to be transmitted. When one of the beams 94, 95 and 96 strikes the plate 8 it causes an emission of secondary electrons varying in amount in accordance with its intensity, and thus the scanning of the plate 8 by these beams causes beams of secondary electrons focused by the lens 13 to scan the mosaics 4, 5 and 6 and record the messages on these. The mosaics are scanned also successively by a fast-moving beam of electrons from the gun 7 in a time at the most equal to the time taken for one scanning of a mosaic by the above mentioned beams of secondary electrons, and this scanning converts the records into signalling impulses with which a carrier wave is modulated and transmitted. At the substation shown in Figure 3 the receiving antenna picks up all the signalling impulses transmitted from the central station, and the intensity of the fast-moving electron beam from the gun 9a, which scans the plate 81a synchronously with the scanning of the plate 3 by the beam from the gun 7 at the emitter, is modulated in accordance with them. There is thus produced a beam of secondary electrons of variable intensity which scans the plate 31a but leaves a record only during a part of this scanning, namely, when it traverses the

mosaic 41a. It thus leaves a record only of the signalling impulses corresponding to the message impressed on the beam of the gun 94 and recorded on the mosaic 4. The mosaic 41a is scanned by a slow-moving beam of electrons from the gun 74a synchronously with the scanning by the beam from the gun 94 and thus reconstitutes the message which passes to the earphones. At the receivers of the other two substations only the messages recorded on the mosaics 5 and 6 respectively are reconstituted. Thus although all the messages are sent on the same wave length from the central station, each substation effectively receives only the message intended for it.

In a similar way in the transmitter of Figure 4, a slow-moving beam of electrons from the gun 94a modulated in accordance with the message to be sent to the central station scans an area of the plate 8a corresponding to the area of the plate 8 scanned by the beam of the gun 94 synchronously with that beam, and so produces a slow-moving beam of secondary electrons which scans the mosaic 41a and records the message on it. The record on the mosaic is translated into signalling impulses by the fast-moving beam from the gun 7a scanning the mosaic synchronously with the scanning by the beam from the gun 7 at the central station. At the transmitters at the other substations scanning proceeds synchronously with the scanning in the transmitter of Figure 4, but these other substations have only mosaics corresponding in position to the mosaics 5 and 6 respectively at the central station with the result that the formation of signalling impulses begins for example in the second substation only after such formation has ended at the substation illustrated in Figure 4. In one scanning period, that is, in the time required for the beam from the gun 7a to cover the whole of the plate 3a, the receiving antenna 17 at the receiver of the central station picks up successively the signalling impulses coming from the three substations and records these on the mosaics at that receiver appropriate to each. The mosaics 41, 51 and 61 are scanned simultaneously, synchronously with the scanning by the beam from the gun 94a, and in this way the messages transmitted from the substations are reconstituted and sent each to the appropriate set of earphones 19 through the amplifiers 18.

The arrangement shown in Figures 3 and 4 where the mosaics 4a and 41a are on plates identical respectively with the plates 3 and 31 in the central station and occupy the same position on these plates as the mosaics 4 and 41 respectively has the advantage of facilitating construction of the apparatus, since an easy way is provided of assuring the proper position of the mosaics 4a and 41a. It will, however, be clear that the plates 3a and 31a need not necessarily extend beyond the mosaics and that similarly the plates 8a and 81a need not be of an area only equal to the area of the mosaics. When the arrangement of Figure 4 is used, however, it is desirable to provide means for preventing transmission from the antenna 15a except when signalling impulses are being produced in order to prevent at the receiver the beats which would otherwise be caused by phase displacement between the waves received from the different substations. A convenient arrangement for this purpose is shown in Figure 4 where the conductive backing for the mosaic 4a is connected to

the filament 20 of a three electrode tube 21 to the plate 22 of which the antenna is connected. The grid 23 is connected to an anode 24 of a cathode ray oscilloscope 25 containing a plate 26 having an electron emissive area 27 having the same relative position on the plate as the mosaic 4a on the plate 3a. The plate is scanned by a beam of electrons synchronously with the scanning by the beam from the gun 1a. When the surface 27 is scanned there is an emission of electrons which being picked up by the anode 24 causes the grid 23 to acquire a potential such as to allow passage of current through the tube 21 but when the rest of the surface 26 is scanned the potential of the grid 23 is such as to block any passage of current and thus prevent transmission from the antenna 15a.

The invention has been described with relation to one particular form of construction but it will be understood that it is not limited to form thus for example, it can perfectly well be used with the alternative form of construction shown in my prior application referred to. Moreover, it is not essential that scanning of the mosaics by the slow moving and fast moving electron beams proceed simultaneously since this might be effected alternatively as indicated in my prior application.

What I claim is:

1. A multiplex communication system comprising a central station including an envelope containing a number of mosaics, means for scanning said mosaics simultaneously by different slow moving electron releasing beams and means for scanning said mosaics successively by a single fast moving electron releasing beam in a time no greater than that elapsing during the scanning of one area by one of the slow moving beams, and a number of substations no greater than the number of mosaics at the central station and each including an envelope, the envelope at each different substation containing only a single mosaic corresponding in position to a different

mosaic at the central station, means for scanning each single mosaic by a slow moving electron beam synchronously with the scanning by the slow moving electron beams at the central station, and means for scanning each single mosaic by a fast moving electron beam synchronously with the scanning of the mosaic at the central station with which it corresponds in position by the first mentioned fast moving electron beam.

10 2. A multiplex communication system according to claim 1 in which at each substation the slow moving electron releasing beam is adapted to record a message on the single mosaic and the fast moving beam to convert the record into signalling impulses, comprising means for modulating a carrier wave by said impulses, and means for preventing transmission of such wave except when so modulated.

20 3. A multiplex communication system according to claim 1, in which at each substation the slow moving electron releasing beam is adapted to record a message on the single mosaic and the fast moving beam to convert the record into signalling impulses, comprising means for modulating a carrier wave by said impulses, and means for preventing transmission of such wave except when so modulated, said last mentioned means comprising a three electrode tube having a filament to which said carrier wave is fed, a plate 30 connected to an antenna and a grid normally at a potential such as to prevent passage of electrons from said filament to said plate, and an auxiliary tube having an electron emissive plate in a position therein corresponding to the position of the single mosaic in the envelope connected to said grid, and means for scanning said plate with an electron releasing beam synchronously with the scanning of the mosaic in the envelope at the substation by the fast moving electron releasing beam.

FRANÇOIS CHARLES PIERRE HENROTEAU.
